UNITED STATES PATENT OFFICE.

LEON P. LOWE, OF SAN FRANCISCO, CALIFORNIA.

APPARATUS FOR MAKING GAS.

No. 821,594.

Specification of Letters Patent.

Patented May 22, 1906.

Application filed November 8, 1905. Serial No. 286,329.

To all whom it may concern:

Be it known that I, LEON P. LOWE, a citizen of the United States, residing at San Francisco, in the county of San Francisco and State of California, have invented certain new and useful Improvements in Apparatus for Making Gas, of which the following is a specification.

This invention relates to an improved apparatus for making gas, the object of the invention being to provide an apparatus for this purpose which shall be inexpensive in construction, simple in operation, and economical in the consumption of fuel and in repairs.

In the accompanying drawings, Figure 1 is a broken front elevation of the apparatus. Fig. 2 is a plan view thereof.

Referring to the drawings, 1 represents a suitable casing lined with refractory material 2 and divided into two compartments 3 by a wall 4, extending from the bottom of the apparatus to a level near the top, said compartments thus communicating with each other at the top over said wall. The two compartments 3 of the apparatus are identical in construction, each compartment being filled with regenerative material 5, supported upon arches 6, and being provided at the bottom with an opening 7, which may be used either as an inlet for admitting air or steam, the air being introduced by a pipe 8, controlled by a valve 9, and the steam by a pipe 10, controlled by a valve 11, or as an outlet for the products of combustion, said outlet leading to an upwardly-extending pipe 12, controlled by a valve 13 and discharging into a stack 14.

At the top of each compartment 3 there is provided an inlet-pipe 15, through which may be admitted oil injected by steam through a pipe 16. From the bottom of each compartment leads a conduit 17, controlled by a valve 18, said conduits being connected to a common conduit 19, leading downwardly into a washer 20.

The operation of this apparatus is as follows: First, for the preliminary or heating stage the steam-pipes 10 are closed on both sides, the air-pipe 8 is opened on the one side—as, for instance, the right—and closed on the other, the left, the valve 13 is closed on the right and opened on the left, the valves 18 are both closed, and the oil-pipe 15 is opened on the right and closed on the left. Combustion having been started by any

suitable means, the oil admitted on the right is burned by the blast of air admitted at the bottom of the right-hand compartment, and the products of combustion are passed over 60 the top of the wall 4 and down through the left-hand compartment and up through the stack on the left. After the regenerative material in the left-hand compartment has been sufficiently heated, the air and oil pipes are 65 closed on the right and opened on the left and the valve 13 is closed on the left and opened on the right. Combustion now takes place in the opposite direction, the products of combustion passing down through the 70 compartment on the right and heating the regenerative material therein. This process is repeated two or three times until the regenerative material in both compartments has been sufficiently heated for the gas-mak- 75 ing stage to commence. For this purpose, supposing that the last heating operation has been in the direction from right to left, the oil-pipe on the right is closed for a short time, and the air-pipe on the right is shut off and 80 the steam-pipe opened. The valve 13 on the left is closed and the valve 18 on the left is opened. The oil-pipe on the right is now opened more widely than before to supply oil in sufficient quantity to make gas. The 85 steam passing up through the highly-heated regenerative material on the right becomes itself highly heated, and therefore assists in vaporizing the oil admitted through the oil-pipe at the top of the right-hand compart- 90 ment. Said oil is also vaporized by the heat in the top of the casing, and said oil-vapor and steam, passing down through the highly-heated regenerative material in the left-hand compartment, are decomposed and form fixed 95 combustible gases. These gases pass out through the pipe 17 on the left, the valve 18 being open, and thence into the washer 20, whence they pass through the scrubbers and purifiers in the usual manner. After this 100 process has continued for some time the temperature of the regenerative material in both compartments has been so reduced that the gas produced therefrom is too rich and the gas-making operation must now be repeated. 105 For this purpose the oil is shut off and steam alone is passed through both compartments, so as to purge the compartments of gas, and then the steam is shut off on the right, the valve 18 is closed on the left, the valve 13 is 110 opened on the right, and air is admitted on the left. Oil is now again admitted through

the oil-pipe on the left. The air passing up through the highly-heated regenerative material on the left becomes highly heated, and thus produces an economical combustion of the oil admitted at the top of the left-hand compartment. The products of combustion pass down through the highly-heated regenerative material in the right-hand compartment and heat the same, and when said regenerative material has been sufficiently heated the air is shut off on the left, the valve 13 on the right is closed, the valve 18 on the right is opened, and steam is introduced on the left-hand side. The process of making gas is now repeated in the opposite direction, the gas so made passing by the conduit on the right to the washer and thence to the scrubbers and purifiers.

By this apparatus the residual heat of the regenerative material is well utilized, first, to heat the air introduced, producing perfect combustion of the oil in the heating stage, and then to heat the steam in the gas-making stage. For it is to be understood that while the temperature at the close of the gas-making stage is not high enough to satisfactorily produce gas, yet the regenerative material is still at a red heat, entirely suitable for producing a hot blast or for superheating the steam. By providing the two conduits, one leading from the bottom of each compartment, controlled by individual valves, I am enabled to use a single washer in conjunction with the two compartments, thus rendering the whole apparatus economical in construction.

I claim—

1. In an apparatus of the character described, the combination of a suitably-lined casing having a central wall extending from the bottom of the casing to a level near but spaced from the top thereof and dividing the casing into two compartments, communicating with each other over the top of said wall, regenerative material in each compartment, an oil-supply pipe discharging direct into the chamber common to both compartments above the top of said wall, steam and air supply inlets at the bottom of each compartment, an outlet for the products of combustion connected with the bottom of each compartment, means for independently controlling said inlets and outlets, and a conduit to

carry off the manufactured gas leading from the bottom of each compartment, substantially as described. 55

2. In an apparatus of the character described, the combination of a suitably-lined casing having a central wall extending from the bottom of the casing to a level near but spaced from the top thereof and dividing the casing into two compartments communicating with each other over the top of said wall, regenerative material in the compartments, arranged in a continuous pile from the top to the bottom, an oil-supply pipe discharging direct into the chamber common to both compartments above the top of said wall, steam and air supply inlets at the bottom of each compartment, an outlet for the products of combustion connected with the bottom of each compartment, means for independently controlling said inlets and outlets, and a conduit to carry off the manufactured gas leading from the bottom of each compartment, substantially as described. 60 65 70 75

3. In an apparatus of the character described, the combination of a suitably-lined casing having a central wall extending from the bottom of the casing to a level near but spaced from the top thereof and dividing the casing into two compartments communicating with each other over the top of said wall, regenerative material in each compartment, an oil-supply pipe discharging direct into the chamber common to both compartments above the top of said wall, steam and air supply inlets at the bottom of each compartment, an outlet for the products of combustion connected with the bottom of each compartment, means for independently controlling said inlets and outlets, a conduit to carry off the manufactured gas leading from the bottom of each compartment, a common washer into which both of said conduits lead, and means for controlling the passage of the gas through either of said conduits, substantially as described. 80 85 90 95

In witness whereof I have hereunto set my hand in the presence of two subscribing witnesses. 100

L. P. LOWE.
